CAR ROOF

Charles David Bonsall, Pittsburgh, Pa., assignor
to P. H. Murphy Company, New Kensington,
Pa., a corporation of Pennsylvania

Application January 18, 1932, Serial No. 587,196

14 Claims. (Cl. 108—5.4)

This invention relates to car roofs, particularly car roofs with inside carlines. It has for its principal object to provide a roof of this type with means adapted to stiffen and strengthen the roof 5 and also to constitute beams for carrying load-lifting devices. Another object is to provide stirrups that support the load-lifting devices and are slidable on the beams and to provide for their attachment to and removal from the ends of said 10 beams. Other objects are simplicity and cheapness of construction and compactness of design. The invention consists in the arrangements and combination of parts hereinafter described and claimed.

15 In the accompanying drawings, which form part of this specification and wherein like symbols refer to like parts wherever they occur,

Fig. 1 is a plan view of a portion of a car roof embodying my invention,

20 Fig. 2 is a vertical transverse section through one-half of the roof on the line 2—2 in Fig. 1,

Fig. 3 is a vertical longitudinal section through the roof at the ridge on the line 3—3 in Fig. 1,

Fig. 4 is a vertical cross-section on the line 4—4 25 in Fig. 3; and

Figs. 5 and 6 are sectional views similar to Fig. 3 illustrating constructions of modified form.

Referring to the accompanying drawings, my invention is shown in connection with a car roof 30 comprising Z-bar side plates 1 that are connected by car-lines 2 of substantially channel-shaped cross-section with laterally projecting top flanges 3, which serve as supports for the side marginal portions of roof sheets 4. The Z-bar

35 side plates 1 are preferably arranged with their webs horizontal and with their inner flanges projecting upwardly. The carlines 2 gradually decrease in depth from the ridge toward the eaves where they are provided with depending end

40 flanges 5 that overhang and are riveted to the outer faces of the upstanding inner flanges of the side plates 1.

The roof sheets 4 are provided with downturned eaves flanges 6 that overlap the upstanding inner 45 flanges of the side plates 2 and are riveted thereto. The side margins of the roof sheets are overlapped and rigidly secured together and to one of the outstanding top flanges 3 of the carlines by rows of rivets 7. The roof sheets are also secured to the other lateral top flanges 3 of the carlines by rows of rivets 8.

A running board 9 extends longitudinally of the car at the ridge and is supported on top flanges of Z-shaped running board saddles 10, 50 whose base flanges rest on the roof and are rigidly

secured thereto by the rivets 7 that secure the overlapped margins of the roof sheets together and to the top flanges of the channel-shaped inside carlines 2.

Adjacent carlines are connected together, preferably at the ridge, by members that serve as struts to stiffen the roof and as beams for supporting the roof sheets and for carrying load-lifting devices. Each of the beams shown in the accompanying drawings comprises a member or

60 section 11 located above the roof sheets and a member or section 12 located beneath the roof sheets. The upper beam section 11 preferably

comprises a relatively narrow inverted channel of gradually increasing depth from its middle to 65 its ends that extends from carline to carline and has outstanding base flanges 11a that rest on top of the roof sheets 4 and are rigidly secured at

70 their ends to the opposing top flanges 3 of said carlines by the rivets 7 and 8 which secure the roof sheets to said carline flanges. The lower beam section 12 preferably comprises a relatively wide channel that has outstanding base flanges 12a and is disposed beneath said roof sheets with

75 its web riveted to the base flanges 11a of the upper beam section. The base flanges 12a of the lower beam section 12 are adapted to be slidably engaged by stirrups 13 adapted to support a

80 tackle or other load-lifting device (not shown). In each of the lifting beam constructions shown 85 in the drawings, the base flanges 12a of the lower beam section 12 terminate short of the sides of the carlines, thereby permitting the stirrups 13 to be attached to and removed from the ends of

90 said beam section.

In the construction shown in Fig. 3, the lower section of the load-lifting beam is shorter than the distance between the opposing side flanges 3 of adjacent carlines, and has no direct connection

95 at its ends with said carline flanges.

In the construction shown in Fig. 5, the lower section of the load-lifting beam extends beneath and is secured at its top to the undersides of the opposing top flanges 3 of adjacent carlines by the rivets that secure the roof sheets to said flanges;

100 and the base flanges of said lower beam section terminate short of the sides of said carlines to facilitate the attachment of the stirrups to and their removal from the ends of said beam section.

In this construction, the top of the lower beam 105 section is offset downwardly intermediate its middle and ends to provide spaces 15 between said section and the roof sheets so as to permit

ropes or chains to be thrown over said beam sec-

110 tion.

In the construction shown in Fig. 6, the lower section of the load-lifting beam gradually decreases in depth from its middle towards each end, which is closed and rigidly secured flatwise by rivets 14 to the adjacent side wall of the carline. In this construction, the base flanges of the lower beam section terminate short of the ends thereof, thereby permitting the stirrup 13 to be slid on and off the ends of said flanges.

10 By the arrangements described, adjacent carlines are rigidly connected together by members that serve as ties and struts to prevent the carlines from tilting or bowing. These carline connection members also serve as beams for supporting the sheets between carlines; they also serve to distribute the vertical load applied thereto between adjacent carlines; and they also serve as beams for slidably supporting the stirrups to which lifting tackle or other devices may be secured, which stirrups may be readily attached to and removed from the lower members of the supporting beams by sliding them on and off the ends of said beams.

What I claim is:

- 25 1. A car roof comprising carlines, roof sheets spanning the spaces between carlines and rigidly secured thereto and a beam located between adjacent carlines, said beam comprising upper and lower sections located above and below the roof sheets, respectively, and riveted together, the upper section extending from carline to carline and being rigidly secured thereto, and the lower section having supporting flanges terminating short of said carlines.
- 30 2. A car roof comprising carlines, roof sheets spanning the spaces between carlines and rigidly secured thereto and a metal beam extending between adjacent carlines, said beam comprising upper and lower sections located above and below the roof sheets, respectively, and riveted together, the upper section extending from carline to carline and being rigidly secured thereto, and means mounted on said lower section for supporting a load-lifting device, the end portion of said lower section being spaced far enough from the carlines and arranged for the attachment to and the removal of said means from the end of said lower section.
- 35 3. A car roof comprising carlines, roof sheets spanning the spaces between carlines and rigidly secured thereto and a beam extending between adjacent carlines and rigidly secured thereto, said beam comprising upper and lower sections located above and below the roof, respectively, and rigidly secured to said carlines, said lower section being provided with depressions in its upper side that form spaces between said lower section and the undersides of the roof sheets.
- 40 4. A car roof comprising carlines, roof sheets supported on and rigidly secured thereto, and a beam extending between adjacent carlines and rigidly secured thereto, said beam comprising upper and lower sections located above and below the roof, respectively, the ends of the upper section being secured to the tops of the carlines, and the ends of the lower section being secured to the sides of the carlines.
- 45 5. A car roof comprising carlines, roof sheets supported on and rigidly secured thereto, and a beam extending between adjacent carlines and rigidly secured thereto, said beam comprising upper and lower sections located above and below the roof, respectively, the ends of the upper section being secured to the tops of the carlines, and the ends of the lower section being secured to the

sides of the carlines, said lower section being provided with side flanges that terminate short of the sides of the carlines.

6. A car roof comprising carlines, roof sheets supported on and rigidly secured to said carlines, and a load-lifting beam extending between adjacent carlines, said load-lifting beam comprising upper and lower sections located above and below the roof sheets with their ends rigidly secured together to said carlines and to said roof sheets. 80

7. A car roof comprising carlines, roof sheets supported on and rigidly secured to said carlines, and a load-lifting beam extending between adjacent carlines, said load-lifting beam comprising upper and lower sections located above and below the roof sheets with their ends rigidly secured together and to said carlines and said roof sheets, the lower section terminating short of the sides of said carlines. 85

9. A car roof comprising channel-shaped carlines provided with outstanding top flanges, roof sheets supported on and rigidly secured to said flanges, and a metal load-lifting beam extending between adjacent carlines, said beam comprising upper and lower sections located above and below the roof sheets, the upper section having its ends supported by and rigidly secured to the opposing side flanges of adjacent carlines, and the lower section being riveted to said upper section and terminating short of said carlines. 90

100

9. A car roof comprising channel-shaped carlines provided with outstanding top flanges, roof sheets supported on and rigidly secured to said flanges, and a metal load-lifting beam extending between adjacent carlines, said beam comprising upper and lower sections located above and below the roof sheets, the upper section having its ends supported by and rigidly secured to the opposing side flanges of adjacent carlines, and the lower section being riveted to said upper section and terminating short of said carlines, said sections being of inverted channel-shaped section with outstanding base flanges. 105

10. A car roof comprising channel-shaped carlines provided with outstanding top flanges, roof sheets supported on and rigidly secured to said flanges, and a metal load-lifting beam extending between adjacent carlines, said beam comprising upper and lower sections located above and below the roof sheets, the upper section having its ends supported on and rigidly secured to the opposing side flanges of adjacent carlines, and the lower section terminating short of said carlines, said sections being of inverted channel-shaped section with outstanding base flanges. 110

1120

11. A car roof comprising carlines, members located beneath the roof sheets in the space between adjacent carlines with their ends rigidly secured to said carlines, and roof sheets supported on said carlines and members, said members being provided with longitudinal side flanges that constitute slideways and terminate far enough short of the sides of said carlines to permit passage of a load-lifting device into position for engagement with said side flanges. 1135

12. A car roof comprising carlines, roof sheets supported on said carlines and members located beneath and in contact with said roof sheets in the space between adjacent carlines with their ends rigidly secured thereto and adapted to strengthen the roof, afford support for the sheets and constitute load-lifting beams, said members 1145

1150

being of substantially inverted channel-shaped cross-section and having flanges along the edges of their side walls that terminate short of the sides of said carlines to permit passage of a load-lifting device into position for engagement with said side flanges.

13. A car roof comprising carlines, roof sheets supported on said carlines and members located beneath said roof sheets in the space between adjacent carlines with their ends rigidly secured thereto and adapted to strengthen the roof, afford support for the sheets and constitute load-lifting beams, said members being of substantially inverted channel-shaped cross-section with outstanding base flanges that terminate short of the ends of said members to permit passage of a load-lifting device into position for engagement with said side flanges.

14. A car roof comprising carlines, roof sheets supported on said carlines and members located beneath said roof sheets in the space between adjacent carlines with their ends bent downwardly and rigidly secured to the lower portions of the carlines to strengthen the roof and constitute load-lifting beams, said members being of substantially inverted channel-shaped section and gradually decreasing in depth from their middle to their ends and having outstanding base flanges that constitute a slideway for a clevis and that terminate short of the ends of said members to provide sufficient spaces between the ends of said flanges and the carlines adjacent thereto to permit mounting and removal of the clevis therethrough.
